UNITED STATES PATENT OFFICE.

CHARLES M. SEITZ, OF HAVELOCK, NEBRASKA.

PISTON-HEAD.

No. 802,827.

Specification of Letters Patent.

Patented Oct. 17, 1905.

Application filed April 1, 1905. Serial No. 258,369.

To all whom it may concern:

Be it known that I, CHARLES M. SEITZ, a citizen of the United States, residing at Havelock, in the county of Lancaster and State of 5 Nebraska, have invented certain new and useful Improvements in Piston-Heads, of which the following is a specification.

My invention relates to piston-heads for engines, and particularly of the reciprocating 10 type, and has for its object the improvement of piston-heads by which the parts subject to wear may be replaced without removing the head from the piston-rod, which is accomplished by having the head formed of a spider 15 secured to the end of the rod to which is secured wear-plates between which are mounted the bull-ring to receive the packing.

My invention will be fully explained hereinafter and will be found illustrated in the 20 accompanying drawings, in which—

Figure 1 is an end view of a piston-head made in accordance with my invention; Fig. 2, a view in section on the line $x-x$ of Fig. 1, and Fig. 3 a similar view on the line $y-y$ of 25 Fig. 1.

Referring to the drawings, in which similar reference characters indicate corresponding parts throughout the several views, A represents the piston-rod, having a slightly conical-shaped end B with an annular flange C at the 30 inner end of said conical-shaped end.

D represents the foundation of my improved piston-head, which I shall designate as "spider" in the future, and which is mounted on the 35 conical-shaped end C and held in position by means of a nut E, screwed onto a screw-threaded portion F of rod A. The spider D consists, essentially, of a hub G, a plate H, and radial lugs I, having enlarged ends J with 40 screw-threaded sockets K therein.

L represents a plate secured on the front of the piston by means of screw-threaded bolts M, fitting screw-threaded sockets K,

while N represents a plate secured to the rear side of the piston-head by means of 45 countersunk bolts O, secured through holes in plate H and said plate N.

Q represents the bull-ring, secured between the plates L and N and having grooves R to receive the packing S.

By this construction it is readily apparent that the plates L and N sustain the wear to which the edge of the piston-head is usually subjected, and as these may be removed and replaced at will an economical structure is 55 secured and one that can be repaired without removal from the piston-rod. It will be also noted that the bull-ring Q is formed with the grooves R for the packing-rings S on its outer edges, which admits of the use of thicker 60 packing-rings than would be usable if the grooves were intermediate the edges of the ring.

Having thus described my invention, what I claim is—

In a piston-head, a spider comprising a hub adapted to be secured to the end of a piston-rod, a web integral with said hub, and a plurality of lugs extending radially from said hub and formed integral therewith and with 70 said web, said radial lugs being provided with enlarged ends having screw-threaded sockets therein, a plate secured to the front of the spider by bolts secured in said threaded sockets, a plate secured to the back of the spider 75 by bolts secured in the web, and a bull-ring having grooves at the sides of the ring mounted between said plates, substantially as shown and described.

In testimony whereof I hereto affix my signature in the presence of two witnesses.

CHARLES M. SEITZ.
